IMPROVEMENT IN MACHINE FOR MAKING TWINE AND SMALL CORDAGE.

GEORGE A. TAYLOR, LESTER CRANDALL, HORACE L. CRANDALL, AND JONATHAN LARKIN, OF HOPKINTON, RHODE ISLAND.

Letters Patent No. 60,280, dated December 4, 1866.

SPECIFICATION.

TO ALL WHOM IT MAY CONCERN:

Be it known that we, GEORGE A. TAYLOR, LESTER CRANDALL, HORACE L. CRANDALL, and JONATHAN LARKIN, of Hopkinton, in the county of Washington, and State of Rhode Island, have invented a new and useful Improvement in the Manufacture of Twine and Small Cordage; and we do hereby declare that the following is a full, clear, and exact description thereof, which will enable others skilled in the art to make and use the same, reference being had to the accompanying drawings, forming part of this specification, in which—

Figure 1 is a side view of our invention.

Figure 2 is a plan or top view of the same.

Figure 3, a transverse vertical section of the same, taken in the line $z z$, fig. 2.

Similar letters of reference indicate like parts.

This invention relates to a new and useful improvement in mechanism for manufacturing twine and small cordage, and has for its object the twisting of a plurality of cords or lines simultaneously, or at one operation, with one attendant or operator only, and the latter allowed full control over each line or cord during the process of twisting.

A represents an elevated way or rail which extends the whole length of the walk, and has a carriage, B, suspended on it, the carriage being allowed to move freely back and forth thereon. This carriage has a horizontal bar, C, attached to it, the upper surface of which is ground or cut to form a series of what are technically termed "tops," $a \times$. On this bar, C, there are nine "tops" which receive twenty-seven strands, a ; and consequently nine lines or cords, D, will be twisted simultaneously, there being three strands to each line or cord. The strands are supported by rests composed of a series of upright wires or rods, b , attached to a horizontal pivoted shaft, E, which is allowed to turn freely and has a weight, F, suspended from it, which weight has a tendency to keep the wires or rods, b , in a vertical position, said wires or rods serving as guides as well as supports for the strands. These rests are placed at a suitable distance apart, say twenty-five feet, more or less being used according to the length of the building or walk. The strands, a , are connected at one end to the usual rotary spindles which give them the twist, and they are attached at their opposite ends to the ordinary fixtures. As the strands, a , are twisted, the lines or cords, D, are "laid," as it is technically termed, at the rear ends of the "tops," and the bar, C, on which the tops are formed, is moved gradually forward in the direction indicated by arrow 1; the twist of the lines or cords, D, assisted by the hand of the operator, causing said movement. When the bar, C, comes in contact with a series of wires or rods b , on a shaft E, the latter turn or give way before the bar C, the shaft E turning, and when the bar C has passed the wires or rods b , the latter immediately assume their upright position, owing to the influence of the weight, F, and the lines or cords drop into the spaces between the wires or rods, b , which were occupied by their central strands, a . By these means it will be seen that the wires or rods, b , do not interfere at all with the movement of the bar C; and it will also be seen that the operator can reach any of the "tops," or any of the lines or cords or strands, during the twisting operation. Thus a plurality of lines or cords may be twisted simultaneously or at one operation, and the work performed equally as well as if one only were twisted, for the reason that the operator has access to and can reach every line or cord and every strand while being twisted, and can, therefore, in the event of any strand or line being casually displaced, re-adjust the same in proper place. The twisting of a plurality of lines or cords simultaneously has been previously essayed, but not generally adopted on account of the means employed not admitting of the operator having complete control over the mechanism, certain parts of the latter (the way and carriage) interfering with the manipulating of the lines or the strands. Our elevated way and suspended carriage effectually obviate this difficulty.

Having thus described our invention, we claim as new, and desire to secure by Letters Patent—

The elevated way or rail A, provided with the suspended carriage B, having the top bar C attached, all arranged substantially as and for the purpose set forth.

The above specification of our invention signed by us this day of August, 1866.

HORACE L. CRANDALL,
GEORGE A. TAYLOR,
LESTER CRANDALL,
JONATHAN LARKIN.
